Millinocket, Maine

Application February 27, 1939, Serial No. 258,832

6 Claims. (Cl. 128—52)

Our invention relates to therapeutic apparatus. An important object of our invention is to provide an apparatus adapted to be used by physicians whereby a deep-seated mechanical massage or vibratory movement may be imparted to selected portions of the body of a patient to promote the circulation of the blood and lymphatic fluids of the body.

Another object of our invention is the provision of a roller means attached to the apparatus and actuated laterally in a vibratory manner, and adapted to have an axial rotation of the roller simultaneously imparted thereto.

Yet another object of our invention is to provide an apparatus adapted to be used by physicians whereby pressure is alternately applied to different portions of the body, thereby causing a to-and-fro movement of the tissues and fluids of the body to stimulate and pump the blood and lymph fluids forward in their natural channels.

Still another object of our invention is the provision of an apparatus adapted to be used by physicians whereby the speed of the vibratory movement may be manually selectively varied.

A further object of our invention is to provide an apparatus adapted to be used by physicians that includes a support for the body of a patient that may be angularly adjusted with respect to the horizontal.

A still further object of our invention is the provision of an apparatus that is comparatively simple in construction, efficient in operation and inexpensive to manufacture.

Other objects and advantages of our invention will be apparent during the course of the following description:

In the drawings, forming a part of this specification, and in which like numerals are employed to designate like parts throughout the same,

Figure 1 is a side elevation of a device embodying our invention.

Figure 2 is a transverse sectional view, taken on the line 2—2 of Figure 1.

Figure 3 is a vertical sectional view, taken on the line 3—3 of Figure 1.

Figure 4 is a transverse sectional view, taken on the line 4—4 of Figure 3.

Figure 5 is a vertical sectional view taken on the line 5—5 of Figure 4.

Figure 6 is a top plan view of a roller embodying a part of my invention.

Figure 7 is a transverse sectional view, taken on the line 7—7 of Figure 4, and

Figure 8 is a perspective view of the main frame of the device.

In the accompanying drawings, wherein for the purpose of illustration, is shown a preferred embodiment of our invention, the numeral 10 designates a pair of spaced cylinders having the lower ends thereof screw threaded to receive the base caps 11, and the upper ends thereof enclosed by a transverse end wall 12. The wall 12 is provided with an annular recess 13 that tapers inwardly to a substantially smaller bore 14 which is in communication with the interior of the cylinder 10. Pistons 15 are reciprocably mounted within the cylinders, and are formed with piston rods 16 which extend upwardly through the bore 14 and terminate a substantial distance thereabove. The recesses 13 screw threadedly receive packing nuts 17 which compress the packing 18 to make a tight connection between the rod and the cylinder.

An oil reservoir 19 is positioned intermediate of the cylinders 10 and has an electric motor 20 mounted thereon to actuate the impeller 21 and force the oil from the reservoir into the pistons 10 through the pipe fittings, designated generally by the numeral 22. The fittings 22 include a branch 23 leading from the impeller to the lower portion of one of the cylinders and communicating therewith. A cut-off valve 24 is inserted in the branch to control the flow of oil to the cylinder. A second branch 25 leads from the impeller to the other of the cylinders, and is similarly provided with a cut-off valve 26 to control the flow of oil thereto. It may be seen that when the valves 24 and 26 are open, oil will be distributed to each of the cylinders to hydraulically elevate the pistons therein; or that by closing the valve in either of the branches 23 or 25, the oil will flow through the other branch to hydraulically elevate the piston in communication therewith, and that the first-mentioned piston will remain in the initial position.

The frame 37 is of substantially rectangular formation in plan, and comprises a main frame 38 having transverse braces 39 and 40 the ends of which extend beyond the sides 44 and 52 of the frame and the extremities thereof depend therefrom a substantial distance, as illustrated in Figures 1 and 8. The cross braces 39 and 40 are connected by longitudinally extending braces 41 and 42 spaced inwardly from the sides 44 and 52 of the frame, and a web 43 bridges the braces 41 and 42 adjacent the cross brace 40. The longitudinal sides of the frame 38 are formed adjacent the end 59 with depending ears 60 to

which the links 61 are pivotally attached. The free ends of the links 61 are connected by a transversely extending shaft 62 and the middle portion of the shaft is received by the bracket 33 carried by the free end of the subjacent piston rod 16. 5 Adjacent the end 66 of the frame the longitudinal sides 44 and 52 are formed with depending ears 67 which are connected by a transversely extending shaft 68. The middle portion of the shaft is received by the bracket 33 carried by the 10 free end of the other of the piston rods 16.

An equalizer unit is disposed interjacent the cylinders 10 and includes a pair of uprights 27 and 28 which have horizontally aligning openings adjacent their top to receive a cross bar 29, the ends of which extend beyond the uprights and have the arms 30 and 31 fastened thereto. The arms are maintained from rotating independently of the cross bar by the set screws 32 and form, in effect, an elongated U-shaped bracket. Link 20 members 35 and 36 are pivotally attached at one end to the extremities of the arms 30 and 31. A collar 63 is secured to the shaft 62 by the set screw 64 and the link 36 is pivotally attached to the laterally projecting boss 65 by the bolt 73. 25 The collar 69 is secured against rotation on the shaft 68 by the set screw 70, and the link 35 is pivotally attached to the laterally extending boss 71 by means of the bolt 72.

The supports 27 and 28, cross bar 29, arms 30 and 31 and links 35 and 36 comprise an equalizer, or stabilizing unit which, when attached to the piston rods, prevents either of the said piston rods from being elevated faster than the other, and assures the horizontal alignment of the upper ends of the rods at all times. It is obvious that the equalizer will only be connected to the piston rods at such times as it is desired to evenly and simultaneously elevate or lower the pistons. If it is desired to raise one but not the other of the pistons it will be necessary to disconnect the equalizer from the piston rods by removing the bolts 72 and 73. The link members 35 and 36 and arms 30 and 31 may then be lowered into engagement with the floor or other supporting object. 45

The side 44 of the frame 38 has a pair of depending arms 45 and 46 formed integrally therewith and, pivotally attached between the ends thereof, is the head of a T-shaped lever 47. The depending shank 48 of the lever is rigidly secured to a motor housing 49, and pendulously supports the same from the frame. The lower portion of the motor housing is formed with an ear 50 to which is pivotally attached a lever arm 51. The side 52 of the frame 38 has an arm 53 formed thereon and depending therefrom to receive the free end of the lever 51 through the opening 54. The lever 51 terminates exteriorly of the arm 53 in a laterally extending handle 55. The opening 54 has an upwardly extending tooth 56 which engages with the coacting teeth 57 formed in the lower edge of the lever 51, and a spring clip 58 has one end bolted, or otherwise secured, to the arm 53 and the other end thereof frictionally engages the upper edge of the lever to maintain the teeth of the same in engagement with the tooth 56. It may thus be seen that the motor 49 may be pendulously positioned with respect to the frame 38 by manually grasping the handle 55 of the lever 51 and imparting an axial 70 movement to the lever in a manner whereby the tooth 56 in the opening 54 will engage a selected one of the teeth 57.

The gear housing 76 is supported from the frame 38 by the arm 74 which depends from the 75

web 43. Extending transversely of the frames 38 through the sides of the housing 76 and through the packing nuts 77 and 78, is a tubular shaft 79. A circular gear 80 is keyed to the shaft 79 interiorly of the housing 76 and coacting therewith is a worm 81 which is mounted for rotation within the housing. The end 82 of the worm extends exteriorly of the housing through the packing nut 83, and terminates in an enlarged head portion 84. The split pulley 85 is mounted for rotation with the shaft 82, and a spring 86 is interposed between the pulley and the head 84. The inner part 87 of the pulley 85 is fixedly secured to the shaft to prevent a displacement thereof axially along the shaft, and the outer part 88 of the pulley is constantly urged toward the inner part 87 by means of the resilient action of the coil spring 86. Connecting the drive shaft of the motor 49 and the pulley 85 is a V-belt 89, by which rotation of the worm is effected.

The ends of the tubular shaft 79 are supported by arms 90 and 91 which depend from the frame 38. The end 92 of the tubular shaft carries an inner disk 92 the periphery of which is provided with a peripheral notch 95. A solid shaft 96 is mounted for rotation within the hollow shaft 79 and the extremities thereof extend a substantial distance beyond the hollow shaft. The end 97 of the solid shaft has an outer disk 98 fixedly secured thereon and the periphery of the disk is similarly provided with diametrically opposed notches 99 and 100. A key 101 is pivoted to the inner face of the inner disk 92. The key is formed with an outwardly extending tongue 102 of sufficient length to extend through the notch 95 of the inner disk and the peripheral notch 100 in the outer disk 98. The key is provided rearwardly of the fulcrum with a shank 103 under which is seated a coil spring 104 which is sufficiently resilient in its action to hold the key normally engaged in the notches when once so positioned, but will permit the manual disengagement of the key with the disk 98 when desired. The end 105 of the shaft 96 carries an inner disk 106 thereon for rotation therewith, and the hub 107 thereof abuts the end of the hollow shaft 79. The periphery of the inner disk is formed with a notch 110. The solid shaft 79 extends beyond the inner disk 106, and a loosely mounted outer disk 111 is carried thereon. The washers 112 on the extremity of the solid shaft permit the outer disk 111 to have a free independent rotation on the shaft, but prevents the same from being axially displaced along the shaft. The inner face of the inner disk 106 is similarly provided with a key 113 which is adapted to engage either of the diametrically opposed recesses 114 and 115 in the outer disk 111. Coil spring 116 is positioned between the key and the inner face of the disk to normally hold the outwardly extending end of the key in engagement with the notches in the disk 111.

The ends of the transverse braces 39 and 40 extend beyond the longitudinal sides 44 and 52 of the frame 38 and the extremities thereof depend downwardly therefrom to terminate a substantial distance above the gear housing 76. Cylindrical drums 117 and 118 are mounted for rotation between the ends of the braces 39 and 40. The drums are formed with laterally extending end walls 119 and 120 which carry longitudinally extending bars 121 in spaced parallelism with the drums. The disk 98 has an outwardly extending boss 122 adjacent its periphery, and pivoted thereto is one end of a flexible strap

123. The opposite end of the strap is wound about the drum 118 and securely fastened thereto. The outer disk 111, on the end 105 of the shaft 96, is provided with an outwardly extending boss 124. The flexible strap 125 has one end pivotally attached to the boss 124, and its other end thereof is wound around and secured to the drum 117. The braces 41 and 42 of the frame 38 have bearing blocks 126 bolted or otherwise secured to their underside, and the levers 127 are fixedly secured to the outer end of the small shafts 128 which extend through the said bearing blocks. Levers 129 are fixedly secured to the inner end of the shafts 128 and are formed with an upwardly extending shank 130 and a lower shank 140 which extends outwardly and downwardly therefrom. The coil springs 141 are attached to the extremity of the shanks 140, and the other ends thereof are fastened to shanks 14 extending laterally from the supporting arm 14. The depending extremities of the transverse brace 39 have pulleys 142 extending inwardly therefrom in angular relation therewith to properly accommodate the cables 143. Cables 143 have their outer ends wound about and secured to the drums 117 and 118, and the inner ends thereof are attached to the lower extremity of the lever 127.

The frame 38 has rollers 144 mounted for rotation at spaced intervals along its upper surface, and the bed frame 145 is formed with longitudinally extending runners 146 which are adapted to rest on the rollers 144. The spring 148 has one end attached to the arm 147 depending from the bed frame, and the other end thereof is secured to an upwardly extending flange 149 of the frame 38. The spring 148 will permit the frame 145 to have a longitudinal sliding movement with respect to the frame 38, but the resilient action thereof will return the bed frame to the initial position after each longitudinal displacement. The shanks 130 of the levers 129 have pusher rods 150 fastened to the end thereof in a manner whereby the outer ends of the pusher rods bear against the depending abutments 151 formed on the bed frame 145.

The upper surface of the frame 145 is provided with a pad 152 which will comfortably accommodate the recumbent form of a patient. Straps 153 and 154 have their lower ends secured to the rods 121 and extend upwardly through elongated slots 155 and 156 in the bed frame. The straps are coupled above the frame 145 by a suitable buckle connection 157. One end of the bed frame 145 is formed with an upwardly extending flange 158 to which is riveted, or otherwise secured, a pair of straps 159 to receive the feet of the patient and the other end of the bed frame has a pillow 160, or the like, fastened thereto to accommodate the head of the patient.

The operation of our device is as follows:

The patient desiring treatments is placed on the bed frame 145 in a recumbent position, and the straps 153 and 154 are pulled tightly around his waist to securely hold him on the frame. If it is found to be necessary, such additional straps may be attached to the frame as are required to hold the patient securely positioned thereon, or adjustable straps may be secured to foreign objects in close proximity to the device to permit the patient to grasp the same in a manner to steady and brace himself. The adjustable straps 159 attached to the foot portion are buckled around the feet of the patient to hold his feet pressed against the foot board 158.

As hereinbefore described, when the equalizing linkage, comprising the cross bar 29, and links 30, 31, 35 and 36, are secured to the collars 69 and 63 by the bolts 72 and 73, the bed frame 5 145 will be raised in an even horizontal position. However, if the bolts 72 and 73, which connect the linkage to the piston rods, are removed so that the linkage will be disconnected from the hydraulic mechanism, the bed frame may be 10 raised in any angular position by properly manipulating the valves 24 and 26 in a manner whereby the supply of oil will be cut off from one of the cylinders 10. When the equalizer is disengaged from the hydraulic mechanism the linkage may be lowered into engagement with the floor, or other supporting object, until such time as its use is required.

When the motor 49 is energized it will impart rotation to the worm 81 through the V-shaped belt 89. The shaft 82 of the worm carries a split pulley, the outer half of which is maintained in pressed relation with the inner half by means of the coil spring 86. If the motor 49 is manually moved closer to the shaft 82 by means of the hand lever 57, the split sections of the pulleys will move toward each other to increase the ratio between the pulley diameters and to decrease the speed of rotation of the shaft 82. If, however, the motor 49 is moved away from the shaft 82 and locked in this position by the interlocking of the teeth 57 and tooth 56 in the lever arm and supporting arm respectively, the belt 20 will cause the pulley sections to spread apart against the resilient action of the spring 86 to 25 decrease the ratio between the pulley diameters and to increase the speed of rotation of the shaft 82. This arrangement provides a convenient and expeditious means for progressively increasing or decreasing the speed of the mechanism hereinafter described.

The worm 81 coacts with a circular gear on the tubular shaft 79 to rotate the same. The inner disk 92 is keyed to one end of the tubular shaft 79 and consequently will rotate in accordance 30 with the worm gear 81. If the key 101 on the disk 92 is inserted in one of the notches 99 or 100 in the outer disk 98, the rotation of the inner disk will be transmitted to the said outer disk. Inasmuch as the outer disk is keyed to the end of the inner solid shaft 96, the inner disk 106 on the opposite end of the shaft will be caused to rotate in direct ratio to the disk 92. If the key 110 is then positioned to engage either of the notches 114 and 115 in the outer disk 111, the rotation of this disk will be in direct 35 relation with the rotation of the disk 106. The bosses 122 and 124 on the outer disks 98 and 111 act as eccentrics for the straps 123 and 125, and as the outer disks rotate the pull of the straps on the drums 117 and 118 will cause the same to rotate axially. As the bosses on the outer disks rotate past the lowest point, the pull on the drums will be released to permit the coil springs 141 to rotate the drums back to the initial position. The springs 141 transmit action through the levers 129, shafts 128, levers 127 and cables 143. The cables are wrapped about and secured to the drums. If the keys 101 and 110 are engaged in the notches 99 and 114 of the outer disks, the actuation of the drums 117 and 118 will be in unison inasmuch as the notches 99 and 114 are similarly positioned on the drive shaft 96. This will cause the straps 153 and 154 that are buckled about the patient's 40 waist, to be simultaneously given a downward

pull on either side. When this movement is sufficiently rapid, a pulsating movement will be imparted to the straps 153 and 154 which, when in engagement with the body of the patient, will promote the circulation of the blood and lymphatic fluids of the body.

If the keys 101 and 110 engage the diametrically opposed notches 98 and 115, alternate tugs will be imparted to the strap 153. The strap 153 will be pulled downwardly during the downward rotation of the boss 124, and during this period of rotation the boss 122 on the disk 98 will be rotating upwardly and releasing the tension on the strap 154. As soon as the boss 124 starts to rotate upwardly, the boss 122 will be starting in a downward movement to exert a pull on the strap 154. This will cause the belt to be given a sliding movement laterally across the back or shoulders of the patient lying on the table, and a massaging movement will be effected.

If the key 110 is positioned in the notch 115, and the key 101 positioned in the notch 100 a pulsating motion will be imparted to the belts 153 and 154. The notch 100 has the side 108 thereof beveled so that the key may slip out of the notch if sufficient torque is applied to the disk. Inasmuch as notches 100 and 115 are similarly positioned on the shaft, the pull on the belts 153 and 154 will be effected simultaneously. When the boss 122 on the disk 98 passes the lower position, the spring 141 pulling on the cable 143 through the drum 118 will turn the disk 98 a part of a revolution ahead of the disk 111. The torque applied by the spring through the drum and strap 123 will be sufficient to cause the key 101 to slip from the notch 100 and let the disk 98 be pulled ahead of the disk 111. The rotation of the inner disk 92 by the circular gear 80 will cause the key to once more engage the notch 100 after a half a revolution and engage the radial wall 100' of the notch to once more impart rotation to the disk 98. Consequently, as soon as the disks return to a position where the bosses 122 and 124 are in their lowermost position, the action of the springs 141 will again move the disk a half a revolution ahead of the drive mechanism. This will cause a strong downward pull upon both ends of the strap accompanied by a quick upward release at every revolution of the drive shaft 96. This movement will cause a rapid pulsating movement to be imparted to the straps 153 and 154 to stimulate and pump the blood and lymph fluids of the body forward in their natural channel. At every rotation of the drums 117 and 118, a longitudinal reciprocatory movement will be imparted to the frame 145 through the pusher rods 150. In view of the fact that the straps 153 and 154 are attached to the non-reciprocating bars 121 and pulled tightly across the body of the patient, a longitudinal movement of the frame 145 in the direction of the feet of the patient will cause a tensile stress to be applied to the portion of the body below the straps. If the disks are in the position whereby simultaneous tugs are imparted to the ends of the straps 153 and 154, the pusher rods 150 will actuate the bed frame 145 to stretch both of the patient's legs, and if but one of the patient's feet is secured by the straps 159, the legs of the patient may be alternately stretched.

We have provided a massager 160 comprising a U-shaped support 161 terminating at its open end in looped portions 162 which receive the ends of the straps 153 and 154. A handle 163

is secured to the closed end of the U-shaped frame 161 and the roller 164 is rotatably journaled between the arms of the frame 161. When the device is buckled to the straps 153 and 154 and the patient lying face downward on the mat 152, the straps 153 and 154 will impart a lateral vibratory movement to the massager and the operator may manually impart an axial rotation to the roller to effectively massage the patient's back or chest.

It is to be understood that the form of our invention, herewith shown and described is to be taken as a preferred example of the same, and that various changes in the size, shape and arrangement of parts may be resorted to without departing from the spirit of our invention, or the scope of the appended claims.

Having thus described our invention, we claim:

1. A therapeutic apparatus comprising a supporting superstructure, a frame slidably supported on the superstructure, resilient means attached to the superstructure and to the said frame, a motor, a lever pivotally attached to the superstructure and engaging the frame, straps extending transversely of the frame and across a person lying thereon, and an oscillating means actuated by the motor operatively connected to the lever to impart a longitudinal motion thereto and to the frame against the action of the said resilient means and connected to the said straps to simultaneously impart an up and down motion thereto, the simultaneous movements of the frame and straps effecting pulsating agitation of the person lying on the frame.

2. In a therapeutic apparatus, a frame adapted to support the body of a patient, cylinders rotatably mounted on the said frame, resilient means to normally hold the cylinders against rotation, a hollow shaft rotatably carried by the frame below the said cylinders, means to rotate the said shaft, a disk carried by one end of the said hollow shaft and rotatable therewith, a shaft rotatable within the hollow shaft, disks carried by the ends of the said second-mentioned shaft, the disk at the end adjacent the first-mentioned disk being fixedly secured to the shaft and the other of the disks being independently rotatable therewith, means to detachably lock the first-mentioned disk to the fixedly secured second-mentioned disk, means to detachably lock the independently rotatable second disk for rotation with the shaft, eccentrics on the said second-mentioned disks, straps connecting the eccentrics to the cylinders to rotate the said cylinders against the action of the said resilient means, and straps adapted to girdle the body of the patient and having one end fastened to the cylinders so that a tensioning of the straps will be effected during each rotation of the said disks.

3. In a therapeutic apparatus, a frame adapted to support the body of a patient, cylinders rotatably mounted on the said frame, spring means to normally hold the cylinders against rotation, a hollow shaft rotatably carried by the frame below the said cylinders, means to rotate the said shaft, means to manually vary the speed of rotation of the said shaft, a disk carried by one end of the said hollow shaft and rotatable therewith, a shaft rotatable within the hollow shaft, disks carried by the ends of the said second-mentioned shaft, the disk at the end adjacent the first-mentioned disk being fixedly secured to the shaft and the other of the disks being independently rotatable therewith, means to detachably

lock the first-mentioned disk to the fixedly secured second-mentioned disk, means to detachably lock the independently rotatable second disk for rotation with the shaft, eccentrics on the said second-mentioned disks, straps connecting the eccentrics and the cylinders to rotate the said cylinders against the action of the said resilient means, and straps adapted to girdle the body of the patient and having one end fastened to the cylinders so that a tensioning of the straps will be effected during each rotation of the said disks.

4. In a therapeutic apparatus, a frame adapted to support the body of a patient, cylinders rotatably mounted on the said frame, yieldable means to normally hold the cylinders against rotation, a hollow shaft rotatably carried by the frame below the said cylinders, means to rotate the said shaft, a disk carried by one end of the said hollow shaft and rotatable therewith, a shaft rotatable within the hollow shaft, disks carried by the ends of the said second-mentioned shaft, the disk at the end adjacent the first-mentioned disk being fixedly secured to the shaft and the other of the disks being independently rotatable therewith, means to detachably lock the first-mentioned disk to the fixedly secured second-mentioned disk, means to detachably lock the independently rotatable second disk for rotation with the shaft, eccentrics on the said second-mentioned disks, straps connecting the eccentrics and the cylinders to rotate the said cylinders against the action of the said yieldable means, straps adapted to girdle the body of the patient and having one end secured to the said cylinders in a manner whereby a transverse sliding movement is imparted to the said straps upon actuation of the cylinders, and a roller means carried by the straps and contacting the patient.

5. In a therapeutic apparatus, a frame adapted

to support the body of a patient, cylinders rotatably mounted on the said frame, yieldable means to normally hold the cylinders against rotation, a hollow shaft rotatably carried by the frame below the said cylinders, means to rotate the said shaft, a disk carried by one end of the said hollow shaft and rotatable therewith, a shaft rotatable within the hollow shaft, disks carried by the ends of the said second-mentioned shaft, the disk at the end adjacent the first-mentioned disk being fixedly secured to the shaft and the other of the disks being independently rotatable therewith, means to detachably lock the first-mentioned disk to the fixedly secured second-mentioned disk, means to detachably lock the independently rotatable second disk for rotation with the shaft, eccentrics on the said second-mentioned disks, straps connecting the eccentrics and the cylinders to rotate the said cylinders against the action of the said yieldable means, straps adapted to girdle the body of the patient and having one end secured to the said cylinders in a manner whereby an oscillatory movement is imparted to the said straps, a roller carried by the straps and contacting the patient, and a handle means carried by the roller whereby an axial rotation may be effected simultaneously with the oscillatory movement imparted by the straps.

6. In a therapeutic apparatus, the combination of a rotatable hollow shaft, gear means to rotate said shaft, a disk keyed to one end of the shaft, a shaft mounted for rotation in said hollow shaft, disks mounted on both ends of the said second-mentioned shaft, and means to detachably lock the first-mentioned disk to one of the second-mentioned disks thereby imparting rotation to the said second-mentioned shaft.

LLOYD W. MOREY.
EVERETT A. BUCK.
